UNITED STATES PATENT OFFICE.

WILLIAM D. MACQUESTEN, OF MOUNT VERNON, NEW YORK, ASSIGNOR TO THE ABC COMPANY, INC., A CORPORATION OF NEW YORK.

WASHING-MACHINE.

1,127,473.

Specification of Letters Patent.

Patented Feb. 9, 1915.

Application filed November 5, 1913. Serial No. 799,395.

To all whom it may concern:

Be it known that I, WILLIAM D. MACQUESTEN, a citizen of the United States, residing in Mount Vernon, county of Westchester, and State of New York, have invented an Improvement in Washing-Machines, of which the following description, in connection with the accompanying drawings, is a specification, like characters on 10 the drawings representing like parts.

This invention relates to a washing machine or apparatus especially designed and adapted for washing articles of fibrous materials, such for instance as the ordinary 15 family wash.

The invention has for its object to provide a simple and efficient apparatus with which the fibrous articles may be thoroughly washed in a minimum time and with the 20 least possible expenditure of power, either manual or mechanical.

In the present instance, the invention is shown as embodied in a manually operated machine or apparatus, which is particularly 25 adapted for household use, with the ordinary set tubs commonly found in households, suites, flats and the like.

In accordance with this invention, I employ a reciprocating device having its lower 30 end within the tub to engage the clothes or other fabrics therein, and having its upper end extended up out of the tub, and mechanism for reciprocating said device. The device referred to may and preferably will be 35 a plunger or rod provided at its lower end with a cup or hollow head, preferably imperforate for a purpose as will be described, and the mechanism for reciprocating said plunger may be power operated or as herein 40 shown it may be manually operated. Provision is made for reciprocating a plurality of the plungers alternately as will be described. Provision is further made for agitating the clothes by the plungers on their 45 downward movement, as will be described. Provision is also made for readily attaching and removing the apparatus to and from the tub. These and other features of this invention will be pointed out in the claims at 50 the end of this specification.

Figure 1 is a plan view of a single tub provided with a washing machine or apparatus embodying this invention. Fig. 2, a

rear elevation of the apparatus shown in Fig. 1 looking toward the left, showing one of 55 the cups or heads in section, and also the tub in section. Fig. 3, a side elevation of the apparatus, with the tub in section.

In the present instance I have shown the invention as embodied in a hand operated 60 apparatus or machine, which is provided with a plurality of reciprocating devices, b, c, herein shown as two in number and each comprising a plunger, rod or bar 10, provided at its lower end with a cup or bell 65 shaped hollow head 12, which may be detachably secured to the plunger 10 by a screw 13 passed through a washer 14 and the bottom of the head 12 and into a threaded socket in the end of the plunger, or it 70 may be otherwise secured.

The reciprocating devices b, c, have their lower ends located in the tub d, which may be of any suitable or usual construction, such as now commonly found in the laundry 75 rooms and kitchens of households, and the said devices are operatively connected with a rotatable shaft 15, which is shown in the present instance as a rock shaft, mounted to turn in brackets or arms 16, 17, see Fig. 3, 80 attached to hubs 18, 19, which are adjustable on a supporting frame, herein shown as a rod 20, which is secured in fixed relation to the tub d, as will be described.

The rock shaft 15 has fast on it a lever 85 or walking beam 21, having its opposite ends pivotally connected with the upper ends of the plungers 10 of the reciprocating devices b, c, so that, when the shaft 15 is rocked, the devices b, c, are reciprocated in 90 opposite directions. It is preferred to connect the plungers 10 to the opposite ends of a second lever or walking beam 22, which is located below the lever or beam 15 and is mounted on a pivot pin or shaft 23, which 95 is located in a vertical plane with the rock shaft 15, and is supported by an arm or bracket 24 depending from the hub 19. The shaft 15 may be oscillated by means of a crank or handle 25.

The hubs 18, 19 are slideable on the rod 20 to adjust the cups or heads 12 with relation to the tub, and may be split and clamped in their adjusted positions by set screws 26, 27, in a manner well understood.

The rod 20 is provided at its rear end as

herein shown with a cross bar or head 30, having a split hub 31, which is secured to the said rod by a set screw 32, and the said cross bar is provided on its underside with 5 hooks or fingers 33, which are adapted to be passed down through holes 34 in a supporting plate 35, which rests upon the rear wall 36 of the tub and is secured by screws 37 or otherwise to a back board 38. The 10 front end of the supporting rod projects over the front wall 39 of the tub, and is secured in fixed relation thereto, which may be accomplished as herein shown, by means of a clamp screw 40, mounted to turn in an 15 arm 41 depending from a split hub 42, which is clamped to the rod 20 by the set screw 43. The arm 41 is inclined and is substantially parallel with the inclined front wall 39 of the tub, so that when the set screw 20 is set up, the pressure is substantially at right angles to the inclined front wall of the tub, which affords a broad surface for the head of the screw to bear against.

When the screw 40 is set up, the apparatus 25 is firmly secured to the hub, as the screw draws the rod 20 forward, until the locking fingers or hooks 33 are in firm engagement with the metal plate 35.

In operation with the apparatus herein 30 shown, the clothes to be washed, which are not herein shown, are placed in the tub *d* containing soapy water or other washing solutions, and the operator then rocks the shaft 15 by means of the handle 25. On 35 the movement of the rock shaft in one direction, the plunger *b* on one side of the rock shaft is moved downwardly in a substantially straight path, and the plunger *c* on the other side of the rock shaft is moved 40 upwardly as represented in Fig. 2, and on the movement of the rock shaft in the opposite direction, the movements of the plungers are reversed. Inasmuch as the action of each plunger and its cup or bell shaped 45 hollow head is the same, a description of the action of one will suffice. On the downward movement of the plunger, the open mouth of the cup or hollow head is closed by the water, and the air in the cup is confined therein and is compressed by the water which enters the cup and fills the same, more or less. The cup on its downward movement into the water comes in contact with the clothes and its open mouth is more 55 or less closed by the same, with the result that the water is forced through the meshes or interstices of the fabric, and on the upward movement of the cup the pressure upon the air confined in the cup is with- 60 drawn and more or less of a vacuum is created in the cup, which has a suction effect on the water and draws it in the opposite direction through the meshes or interstices of the fabric, and the dirt is thus 65 loosened from the fabric and by repeated

operations is effectively washed from the same. By connecting the plunger to two parallel levers, the plunger is not only moved in a substantially straight path but is supported against lateral displacement 70 when the cup or hollow head strikes or is engaged with the clothes, and is maintained in a substantially straight path in its downward movement. The levers, however, effect a slight lateral movement of the cups 75 toward each other at the end of each down stroke of the plunger, which serves to agitate the clothes and to move the same, so that untreated portions are brought beneath the cup and into position to be effectively 80 acted upon by the same. In addition to the action of the water, which surges back and forth through the meshes of the clothes, the latter are subjected to a pounding action by contact with the cup, and this pounding 85 action also assists in freeing the dirt from the clothes. The steps of the ordinary method of washing the clothes are pursued with this apparatus, that is, after the clothes have been subjected to the action of the 90 reciprocating plungers in a bath of soapy water, the latter may be run off from the tub, and the latter supplied with clean water, and the clothes are again subjected to the action of the apparatus. 95

Experience with an apparatus such as herein shown, has demonstrated the fact that clothes or other fabrics can be washed in a minimum time, with a minimum expenditure of effort on the part of the operator, and at the least possible cost. 100

From the above description, it will be seen that the apparatus is capable of being quickly and easily applied to any make or shape of set tubs, without injuring the tubs 105 or imposing strain thereon. Further, the mechanism which operates the plungers is capable of adjustment on its supporting frame, so as to adjust the cups or hollow heads with relation to the clothes in the 110 tub. The supporting frame is also adjustable so that it can be fitted to tubs of different sizes.

In the present instance I have shown the invention as embodied in a manually operated apparatus, but it is not desired to limit the invention in this respect. So also I have shown the invention as embodied in one construction of hand operated apparatus but it is not desired to limit the invention 115 to the particular construction shown. 120

It is preferred to provide the plungers with imperforate cup or hollow heads, so as to obtain the full vacuum or suction action as well as the compression action above 125 described, but it is not desired to limit the invention in this respect, as the operating mechanism may be used to advantage with cups having one or more perforations or with solid heads. So also it is preferred to 130

use a plurality of walking beams, but it is not desired to limit the invention in this respect.

Claims:

1. In an apparatus of the character described, in combination, a rotatable shaft, a lever operated thereby, plungers connected with said lever on opposite sides of said shaft and provided at their free ends with hollow heads, a second lever connected with said plungers, a support for said shaft, a frame to which said support is adjustably secured to permit the plungers to be adjusted within a tub, and means for detachably securing said frame in fixed relation to said tub. 55
2. In an apparatus of the character described, in combination, a rotatable shaft, a lever operated thereby, and plungers connected with said lever on opposite sides of said shaft, a supporting frame extended across and capable of being detachably secured to one pair of opposite walls of a set tub in fixed relation thereto and between the other pair of walls of said tub, and a bearing for said rotatable shaft having a fixed relation to said supporting frame. 60
3. In an apparatus of the character described, in combination, a supporting frame capable of being applied to and of being removed from a tub, a rotatable shaft, a support for said shaft carried by said frame and adjustable thereon, means to secure said support in fixed relation to said frame, and plungers operated by said shaft. 65
4. In an apparatus of the character described, in combination, a plurality of substantially parallel levers, reciprocating plungers connected to said levers on opposite sides of their pivots, a rock-shaft on which one of said levers is mounted to move therewith, a fixed bearing for said rock-shaft, and means for actuating said rock-shaft to oscillate said levers. 70
5. The combination with a tub, of a washing apparatus coöperating therewith and comprising a plurality of reciprocating devices extended into the tub, and mechanism for simultaneously reciprocating said devices in opposite directions, and means for effecting a slight lateral movement of the devices at the end of their strokes within the tub and a supporting frame for said parts extended across and detachably secured to said tub. 75
6. In an apparatus of the character described, in combination, a rock-shaft, a fixed bearing therefor, a lever secured to said rock-shaft to be rocked with said shaft and extended in opposite directions therefrom, plungers pivotally attached to said lever to be suspended therefrom on opposite sides of said rock-shaft and provided at their lower ends with hollow heads, said plungers being reciprocated by rocking of said shaft, means for connecting the said plungers together below said rock-shaft, and means for rocking said shaft to oscillate said lever and reciprocate said plungers. 80
7. In an apparatus of the character described, an upper lever, plungers pivotally connected with said lever on opposite sides of its pivot, and provided with cups at their free ends, a fixed support for said lever, a lower lever connecting said plungers together near the said cups, a separate support for said lower lever, a frame located between said levers and to which said supports are secured, and means connected with the upper lever to oscillate the same. 85

In testimony whereof, I have signed my name to this specification in the presence of two subscribing witnesses.

WILLIAM D. MacQUESTEN.
